UNITED STATES PATENT OFFICE.

EDWARD R. MULLETT AND WALTER D. FOWLER, OF BRIDGEVILLE, DELAWARE.

CUREYCOMB.

1,164,304.

Specification of Letters Patent. Patented Dec. 14, 1915.

Application filed July 2, 1912. Serial No. 707,337.

To all whom it may concern:

Be it known that we, EDWARD R. MULLETT and WALTER D. FOWLER, citizens of the United States, residing at Bridgeville, in the county of Sussex, State of Delaware, have invented certain new and useful Improvements in Currycombs; and we do hereby declare the following to be a full, clear, and exact description of the invention, such as will enable others skilled in the art to which it appertains to make and use the same.

This invention relates to that class of curry combs which are provided with cleaning plates adapted to remove matted hair and the like from the comb teeth by a scraping action.

An object of the present invention is to provide a curry comb of this type in which the opposite end edges of the teeth are formed with rabbets in which the connecting strips of the cleaning plates work, whereby the annoying binding between the cleaning plates and curry comb teeth often resulting from the spring controlled cleaning plate actuating member of ordinary combs becoming bent, is positively obviated.

A further object of the invention is to provide an extremely simple and strong scraping member in the nature of a plurality of hollow oblong scraping plates each formed from a single blank of sheet metal, all of the scraping plates being connected together by a pair of parallel strips secured transversely across the webs of the plates near the ends, these strips when in operation performing the additional function of guides for directing the sliding movements of the scraping member.

With the above objects in view the invention consists of certain novel details of construction and combination of parts herein-after fully described and claimed, it being understood that various modifications may be made in the minor details of construction within the scope of the appended claim.

In the accompanying drawing forming part of this specification:—Figure 1 is a side elevation of the curry comb. Fig. 2 is a front elevation of the curry comb. Fig. 3 is a longitudinal sectional view through the curry comb. Fig. 4 is a cross sectional view through the curry comb. Fig. 5 is a plan view of the blank from which one of the scraping plates is formed. Fig. 6 is a

detail perspective view of the scraping member.

Referring now to the drawing in which like characters of reference designate similar parts, 10 designates the curry comb back 60 from the lower face of which the curry comb teeth 11 depend, the back being equipped with the usual handle 12 for manipulating the comb.

By referring especially to Fig. 2 it will 65 be seen that the opposite end edges of each tooth 11 are cut away to form oblong recesses 13 which terminate short of the working surface of the tooth, and extend upwardly to the comb back.

The scraping member comprises a plurality of hollow scraping plates 14 each formed from a single blank of sheet metal of the general shape shown in Fig. 5, the marginal portions of the blank designated by 75 the numeral 15 being bent toward each other whereby a substantially oblong hollow scraping plate is produced, the web 16 of which is designed to extend along the underneath face of the comb back, and the longitudinal 80 flanges 17 of which are designed to bear against the comb teeth and scrape accumulated hair and the like therefrom.

All of the scraping plates are connected together by a pair of parallel strips 18 which 85 are substantially square in cross section and are riveted or otherwise fixed to the top faces of the webs 16 of the plate near the ends thereof as best shown in Fig. 6. The strips 18 bear within the recesses 13 in the end 90 edges of the curry comb teeth as shown in Fig. 2 and perform the function of guides for directing the sliding movements of the scraping member, the member actuating device which will be presently described 95 being thus relieved of all guiding function.

For actuating the scraping member the two innermost scraping plates are provided intermediate the ends with upstanding pins 19 which extend loosely through a circular 100 orifice 20 formed in the comb back and are terminally connected by a button 21 which may be soldered or otherwise rigidly fixed to the pins. A helical spring 22 encircles both pins and bears terminally against the 105 comb back and against the underneath face of button. Upon the pin being depressed by striking the button against an article or otherwise, the scraping member will remove accumulated hair from the comb teeth, the 110

spring 22 returning the member to released position after each operation.

By virtue of there being two spaced pins employed in connection with a loose helical spring surrounding these pins foreign matter may be easily dislodged from underneath the pin and thus accumulation of foreign matter positively prevented so that the proper working of the device will be at all 10 times assured.

What is claimed, is:—

A curry comb comprising a back, toothed bars depending from the back, a cleaning plate slidably associated with the bars, a 15 pair of spaced pins slidable in the back and

disposed on opposite sides of the intermediate bar, and having their lower ends fixed to the plate, a single button connecting the upper ends of the pins, and a single coil spring surrounding both pins and having its upper end engaged with the button and its lower end engaged with the back. 20

In testimony whereof, we affix our signatures in presence of two witnesses.

EDWARD R. MULLETT.
WALTER D. FOWLER.
